FOUNDATION VENT

Santiago Marin Sola, Miami, Fla.

Application December 13, 1955, Serial No. 552,795

1 Claim. (Cl. 160—104)

This invention generally relates to foundation ventilation and more particularly to an improved foundation vent insert.

Heretofore there have been provided foundation vents having variable vent louvers for closing in the winter season. However, one problem confronting the home owner has been the control of insects in the crawl space under his home. In order to rid the crawl space of insects, it was necessary either to crawl under the entire house dragging an insecticide dispenser around or remove each of the existing foundation vents from the wall, which are normally set in mortar, treat the desired area with insecticide, and then proceed to replace the vents. Besides being a tiresome and time-consuming job, the removal and replacement of the vents often resulted in more expensive repair jobs, such as replacing bricks and blocks, broken as a result of the removal of the vents. Therefore, the primary object of the present invention is to provide a foundation vent insert which may be installed in a foundation in the usual manner and which provides, in addition to serving in the usual manner, an access opening for the insertion of an insecticide hose or pipe or any other discharge nozzle of an insecticide dispenser.

A further object of the present invention is to provide a foundation vent insert which is decorative and attractive in appearance as well as useful.

A still further object of this invention is to provide a foundation insert having an access opening with a closure means therefor which is easily removed and replaced.

Other objects of the present invention will reside in its ease of installation, adaptation for its particular purposes and its relatively inexpensive manufacture and cost.

These, together with other objects and advantages which will become subsequently apparent, reside in the details of construction and operation as more fully hereinafter described and claimed, reference being had to the accompanying drawings forming a part hereof, wherein like numerals refer to like parts throughout, and in which:

Figure 1 is a perspective view of the corner of a building of block construction showing the foundation vent inserts in a typical installation, with parts of the walls broken away;

Figure 2 is a front elevation of the foundation vent insert with a portion of the removable cap broken away showing the tubular access opening; and

Figure 3 is a side sectional view taken substantially along a plane passing upon section line 3—3 of Figure 2 showing the closure cap removed and illustrating in dotted lines the position of the cap when installed.

Referring now to the drawing in detail, it will be seen that the improved foundation vent insert consists of a rectangular frame, referred to in general by the reference numeral 10. The frame 10 is inserted in a foundation wall 12, as shown in Figure 1, with the longer axis lying

2

in a horizontal plane and the frame in a vertical position. The frame 10 has an upper frame member 14 and a lower frame member 16 joined at the ends thereof by end members 18 and 20.

5 As is best seen in Figure 3, the frame members 14 and 16 are of solid construction and are rectangular in cross-section with the larger dimension of the rectangle lying horizontally. The end members 18 and 20 are likewise rectangular in cross-section, thus forming with the frame members 14 and 16 a box-like frame having opposed faces 22 and 24.

Extending radially inward from each of the corners of the frame 10 there are provided four support arms 26 which terminate at a centrally disposed tubular member 28. The axis of the tubular member 28 is horizontally disposed and provides an access opening therethrough from the outer to the inner side of a wall in which the foundation insert is mounted. The arms 26 have an inner face 30 which, together with an inner face

15 32 of the tubular member 28, are in coplanar relation to the inner face 24 of the frame 10. The tubular member 28 extends beyond the outer face 22 of the frame 10, and as best seen in Figure 3, the arms 26 are slightly tapered from the corners to their terminal point at the 20 tubular member 28. Further, the tubular member 28 is provided at the outer end thereof with a threaded portion 34 having an outer face 36 and a stepped outer face or shoulder 38 at the inner termination of the threaded portion 34, the purpose of which will be described 25 30 hereinafter.

As is best seen in Figure 3, there is provided a discular cap 40 having an outer face 42 and a circular aperture 44 which has internal threads 46 and an internal inner face 48. The threads 46 terminate at the face 48 on one end 35 thereof and at an inner face 50 of the cap 40 at the other end. The face 50 is parallel to the face 42 of the cap.

The cap 40 is threadably received on the threaded portions 34 and the face 50 positively engages the face 38 before the face 48 engages and binds on the face 36. In this manner, unnecessary binding is prevented, and thus the cap 40 is more easily removed after it has been in position for a relatively long period of time wherein the threads and abutting surfaces would normally become rusted and hard to separate.

45 There is provided a screen 52 which is suitably attached to the inner faces 24, 30 and 32 and terminates on the outer extremities at the frame 10 and on the inner extremities at the tubular member 28.

50 In use, the foundation insert is installed in a typical wall construction in a position previously described and with the cap 40 facing to the outside of the wall. When desirous of fumigating or spraying the crawl space or internal section of the foundation, the cap 40 is removed and a hose or nozzle inserted through the tubular member 28. The necessary fumigation having been completed, the hose is removed and the cap 40 replaced. In this manner, the entire crawl space may be treated from the various points at which the foundation inserts are located with the entire crawl space being treated without necessity of entering the crawl space.

55 The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

70 What is claimed as new is as follows:

An insert for a foundation wall of a building, said insert comprising an open rectangular frame of sub-

stantial thickness, the opposed edges of the frame being flat, parallel and having substantial width and thickness for supporting a weight load normally supported by a building block, a plurality of inwardly extending arms connected with said frame and having a thickness generally equal to the thickness of the frame, a tubular member having a longitudinal axis parallel to the edges of the frame and supported within the confines of the frame by said arms and being connected with the arms, one face of said frame, arms and tubular member lying in the same plane, a screen member secured to said one face of the frame, arms and tubular member and forming a closure for the frame and permitting passage of air and light but preventing passage of insects, animals and the like, said screen having an opening therein coinciding with the passage defined by the tubular member

5 10 15

thereby providing an access passage through the insert, and a removable cap mounted on the opposite face of the tubular member from the screen and being accessible only from the opposite face of the frame thereby enabling insecticide to be sprayed through the passage defined by the tubular member.
